UNITED STATES PATENT OFFICE.

GEORGE HARVEY, OF WINNIPEG, MANITOBA; CANADA.

CAR-SEAT.

SPECIFICATION forming part of Letters Patent No. 352,055, dated November 2, 1886.

Application filed March 13, 1886. Serial No. 195,110. (No model.)

To all whom it may concern:

Be it known that I, GEORGE HARVEY, a subject of the Queen of Great Britain, residing at Winnipeg, in the Province of Manitoba and Dominion of Canada, have invented certain new and useful Improvements in Car- Seats; and I do hereby declare that the following is a full, clear, and exact description of the invention, which will enable others skilled in the art to which it appertains to make and use the same.

My invention relates to car-seats, the object being to provide a device of this character which may be readily and quickly reversed, and in which the back and seat may be inclined to afford an easy and comfortable support for the traveler.

A further object of the invention is to provide improved means for supporting the back and seat, whereby they are rendered interchangeable—that is to say, the seat may be adjusted to take the place of the back, and the back adjusted to take the place of the seat all at one movement.

With these ends in view the invention consists in the improved construction and combinations of parts, hereinafter fully described, and pointed out in the claims.

In the drawings, Figure 1 is an end elevation of a car-seat embodying my invention. Fig. 2 is a section showing the inner side of one end of the frame, and Fig. 3 is an end elevation showing the seat and back reversed.

Corresponding parts in the several figures are denoted by the same letters of reference.

Referring to the drawings, A represents one of the end rails of the supporting-frame, which is supported by suitable legs, a, and extending upwardly from said end rail are standards b, at the upper end of which is located an arm-rest, B, suitably cushioned, as shown.

C represents the seat, and D the back, which are cushioned upon their innersides, as shown.

E E' represent bars which extend from the seat and back, to which they are pivoted, to a point on the inner side of the arm-rest, at which point they are pivotally connected by a pin, c.

F represents a hinge connecting the back and seat at their meeting sides. If desired, there may be a hinge arranged to connect the

back and seat near each end thereof; or there may be only one hinge employed. In the latter case the hinge would be arranged midway the sides of the back and seat.

G G' represent blocks arranged at each end of the side rail, A, and having vertical openings or passages d, in which work catch-bolts f, having finger-pieces g, by which they may be operated, said bolt being adapted to engage a recess on the under side of the seat, said seat being supported on the block G, and when the seat and back are reversed said catch-bolt in the block G engages a recess in the seat. The catch-bolt in the block G' engages a recess in the lower end of the back, and when the position of the back and seat is reversed said catch-bolt engages a recess, g', in the seat, near the upper end thereof, while the catch-bolt in the block G' engages a recess, h, in the inner end of the seat. It will thus be seen that the seat and back are supported in an inclined position.

H represents blocks secured to the inner side of the end rail, A, and having cushions or blocks i, of rubber or other elastic material. The inner end of the seat rests on one of these blocks, as shown, and when the position of the parts is reversed the back rests on the other block.

I represents a bar pivoted centrally to the inner side of the supporting-frame of the end rail, and having at its upper end a projection, j, which is adapted to engage an opening, k, in the under side of the seat, and which when the back is changed to form the seat engages an opening, l, in the same.

At the side of the seat and back are provided straps m, by which the seat and back are operated.

The operation is as follows: The strap at the side of the seat is pulled outwardly, the catch-bolt having been previously disengaged from the opening upon the under side of the seat. This action draws the seat forward and the bar I swings upon its pivot, and in assuming a vertical position raises the seat and back and disengages the opening in the lower end of the latter from the catch-bolt in the block G'. The seat assumes a vertical position, or nearly so, and the back rests upon the block G, and the catch-bolt therein engages the recess h in

the seat. The back is supported upon the block adjacent to block G, and the projection on the end of the bar I engages the recess l in the back, and the catch-bolt in the block G' engages the opening g near the upper end of the back.

It will be apparent from the above description that the position of the back and seat may be readily and quickly changed when desired, to and with but little trouble or exertion on the part of the person making the change.

Having thus described my invention, what I claim is—

1. The combination, with a supporting-frame, of a seat and back hinged together at their meeting edges, blocks arranged at the front and rear of the supporting-frame and carrying catch-bolts to engage recesses in the seat and back, and bars E E', pivotally connected with the seat and back, and to the arm-rests of the supporting-frame, substantially as set forth.

2. In a car-seat, the combination, with a supporting-frame, of a seat and back, bars pivotally connecting the back and seat with the arm-rest of the frame, and a bar pivoted to the supporting-frame and adapted to engage a recess in the under side of the seat, as set forth.

3. In a car-seat, the combination, with a supporting-frame, of a seat and back hinged together at their meeting ends, bars pivotally connecting the seat and back with the arm-rest of the frame, and a bar pivoted to the frame and having a projection at its upper end to engage a recess on the under side of the seat, as set forth.

In testimony whereof I affix my signature in presence of two witnesses.

GEORGE HARVEY.
